FOLDING CRATE

William Richard Wiley, Altoona, Pa.

Application October 6, 1930. Serial No. 486,834

3 Claims. (Cl. 217—47)

This invention relates to shipping crates and has for its primary object to provide an improved type of collapsible shipping crate that is cheap to manufacture, and when folded for return shipment 5 occupies the minimum amount of space.

Another object of this invention is to provide an improved collapsible shipping crate such that when folded will permit of other similar crates being piled or stacked, one upon the other to any 10 desired height in the carrier, thus conserving space in the carrier for the shipment of other crates or other merchandise.

A further object of this device, is to provide means for locking the crate in its open position 15 as well as locking the same in its folded position ready for reshipment.

A still further object of this invention, is to provide a crate design which is susceptible of being built of aluminum, metal or wood strips, depending upon the service in which the crate is to be used.

With these and other objects in view, which will be more readily apparent as the nature of the invention is better understood, the same consists 25 in the novel construction, combination and arrangement of parts as will be hereinafter fully pointed out, illustrated and claimed.

It will be readily understood by those skilled in the art to which this invention belongs, that the 30 same is susceptible to some structural changes and modifications without departing from the spirit or scope of the invention, but a preferred and practical embodiment of the invention is shown in the accompanying drawing, in which 35 Fig. 1 is a plan view of my improved collapsible crate, shown in its open position, as it would appear when ready to receive such articles as potatoes, apples, oranges or peaches.

Fig. 2 is a side elevation of the open crate shown 40 in Fig. 1 of the drawing.

Fig. 3 is an end elevation of the crate shown in Fig. 2 of the drawing and illustrates the manner in which the sides are folded down when the 45 crate is in its folded or collapsed position.

Fig. 4 illustrates the crate as it appears with its sides folded down into position and the ends being folded into position.

Fig. 5 shows a plan view as the crate appears in its folded position.

Fig. 6 shows an edge view of the folded crate 50 shown in Fig. 5 of the drawing.

Fig. 7 shows the slot in one of the side and bottom members, provided for the crate locking means.

Fig. 8 shows an enlarged view of one corner 55

of the crate with the locking means in position for holding the crate open.

Similar reference numerals refer to similar parts throughout the several figures of the drawing.

In carrying out the objects of this invention I provide a crate base designated by the numeral 10, which consists, in the preferred construction, of a plurality of wood or light metal slats or strips 11, attached to transverse rectangular elements 12. These transverse strips 12 not only provide means for spacing and holding in position the slats or strips 11 but also form means for hinging the ends 13 of the crate, as shown in Fig. 4 of the drawing. The ends 13 of the crate are hinged upon the transverse rectangular strips 12, each of which are the same height and thickness, as clearly indicated in Fig. 2 of the drawing.

The sides 14 and 15 of the crate, are each hinged likewise to permit each to swing into the position it occupies when folded.

The side 14 is hinged to the outermost longitudinal bottom strip or slat 16. The hinge 17 being positioned on the strip 16, a distance from the edge of the crate equal to the thickness of the upright side strip 18; this position being necessary, such that the side strip 18, when the crate is open, will not extend beyond the end of the end strips 12. This provision being necessary in order that the crate may be pushed one against the other 85 when being shipped with merchandise therein.

The opposite side of the crate is provided with a longitudinal strip 19, positioned upon the outer bottom slat or strip 20, and is secured thereto by means of nails or screws. The height of this strip 19 is equal to the combined thickness of the longitudinal strips 21 and the vertical strips 18, to permit the second mentioned side of the crate to be readily folded upon the first mentioned, as shown in Fig. 6 of the drawing.

Fig. 1 illustrates the manner in which the vertical strips 22 and 23 of the respective sides of the crate are positioned on the longitudinal strips of the crate sides in disaligned relation to permit the sides of the crate to fold inward into compact relation, one above the other.

The ends 13 are each hinged upon the end strips 12. The height of each of these strips being equal to three times the thickness of one of the longitudinal side strips. The side and end strips or slats being in the preferable construction of equal thickness and width.

With the crate in its open position and ready to receive merchandise, some means are required to hold the ends as well as the sides in an

upright position, and to this end I provide a locking means, which consists essentially of an L-shaped wire 27, having an offset leg 28 bent at right angles to the foot of the L, and adapted 5 to engage the underside 29 of the top longitudinal strip 30 when in the locked position and the crate open or unfolded and set up. To provide for the most effective locking means the vertical side strip 31 is provided with a slot 32, 10 which is engaged by the wire 27 as indicated in Fig. 8 of the drawing.

When the crate is folded with the top portion of the crate ends adjacent each other, as indicated in Fig. 6, the locking means which is carried by the crate ends are likewise brought adjacent each other, and the crate is locked in its closed position by the same locking elements that lock the crate in its open position, the difference being in the manner the locking means 20 is applied.

When locking the crate in its folded position, the locking wires 27, which face each other when the crate is folded, are each dropped through a slot 33, positioned in the center of the outside bottom slot 34 as indicated in Fig. 7 of the drawing. The locking wires 27 are each pulled toward their respective ends of the crate and wedged in a groove 35 also cut in the member 34 as illustrated.

When unfolding the crate, or setting it in position, to receive merchandise to be shipped, the following operations are performed:

First.—The crate is placed on the floor, with the bottom surface 36 resting thereon.

Second.—The ends 25 and 26 are each unlocked from the bottom member 34, after which the end 25 is raised such as to occupy a vertical position, the end 26 is likewise raised, permitting the side 37 to be raised into position after 40 which the side 38 is elevated into position. The ends are then locked to the side members, and the crate is ready for use.

Having thus described my invention, what I

claim and desire to be secured by Letters Patent is:

1. A foldable box or crate comprising a bottom, side and end elements hinged to the bottom for swinging movements between collapsed and erected positions, the side elements each being inclusive of a longitudinally extending top rail and vertically extending end cleats, the upper ends of the cleats being cut away to provide grooves between their upper end portions and the top rails, respectively, and a pair of hook shaped fasteners pivoted, respectively, to upper corner portions of each end element, each fastener comprising a straight inner end portion to be swung into the related groove of the related side element when the side and end elements are erected, and a right angularly extending portion to lie against the inner edge of the related cleat when the inner end portion is disposed in the related groove. 80

2. A foldable box or crate as set forth in claim 1 in which each fastener comprises a straight inner end portion to be swung into the related groove of the related side element when the side and end elements are erected, a right angularly extending intermediate portion to lie against the inner edge of the related cleat and against a side face of the related top rail of the related side element when the inner end portion is disposed in the related groove, and terminal portion extending at substantially right angles to said intermediate portion to underlie the related top rail when the inner end portion is disposed in the related groove. 90

3. A foldable box or crate as set forth in claim 1 in which the bottom of the crate is provided medially and at each side thereof with a longitudinally extending slot medially opening through the edge of the bottom to receive the outer end portions of the fasteners at the related sides of the end elements when the side and end elements are collapsed. 100
